UNITED STATES PATENT OFFICE.

JOHN E. BLACK, OF MENDOTA, ILLINOIS.

MACHINE FOR EDGE-UNITING VENEERS.

Application filed November 23, 1925. Serial No. 70,977.

This invention has to do with machines for edge uniting veneers. The invention has to do particularly with machines for directly edge uniting the veneer sections without the use of any facing strips of paper, cloth or other material.

The main object of the invention is to provide a machine for directly edge uniting the veneer strips by a continuous longitudinal movement as distinguished from a side-wise or transverse movement of the veneer strips. That is to say, it is an object of the invention to provide means for causing the veneer sections to be brought together and direct edge united by an operation in which the strips travel lengthwise instead of transversely.

It is another object of the invention to provide a machine for heating the edge portions of the strips during the uniting operation so as to assist and improve the hardening action of the adhesive used. In this connection, it is an object to use an adhesive of such composition that its "setting" is dependent rather upon the application of a certain degree of heat as distinguished from a mere drying action due to the application of heat.

Another object of the invention is to provide a machine of very simple arrangement and construction, one which will be rugged and well able to perform the work for which it is intended, and one which shall be cheap to construct and maintain.

Other objects and uses of the invention will appear from a detailed description of the same, which consists in the features of construction and combinations of parts hereinafter described and claimed.

In the drawings:

Figure 1 shows a side elevation of a machine embodying the features of the present invention;

Fig. 2 shows an end view at right angles to Fig. 1;

Fig. 3 shows a fragmentary plan view taken on the line 3—3 of Fig. 2, looking in the direction of the arrows;

Fig. 4 shows a transverse section on the line 4—4 of Fig. 2, looking in the direction of the arrows, but on enlarged scale; and

Fig. 5 shows a fragmentary section on the line 5—5 of Fig. 2, looking in the direction of the arrows.

The machine includes a stand 6 carrying

a table 7 on which the material is supported. A bracket arm 8 reaches out over the table from one side so as to leave a considerable clear space beneath said arm within which the required size of work may be manipulated.

Located in the table and preferably projecting slightly above the surface thereof are the two carriers 9 and 10. These are generally of the chain type, but are preferably relatively thin, so that their surfaces do not project materially or appreciably above the surface of the table.

These conveyors 9 and 10 preferably slant or converge towards each other at one end, as clearly indicated in Figs. 1 and 3. At the front ends where they are most separated, they pass over idler pulleys 11, and at their rear ends where they are close together, they pass over driving pulleys 12. The idlers 11 are carried on a transverse shaft 13. The driving pulleys 12 are carried on another transverse shaft 14 which is conveniently driven in any desired manner from a pulley 15. The details of this drive are not illustrated, since manifestly many different arrangements of drives may be used.

The various pulleys are more or less flexibly carried on the two shafts 13 and 14 respectively, since a sort of universal joint connection is desired, owing to the slight angularity at which the pulleys are placed on the shafts.

Supported by the free end of the bracket arm 8 is a presser head 15. The same includes a series of cross blocks 16, one of which is illustrated in detail in Fig. 4. Each of these cross blocks is spring pressed downwards with respect to the presser head 15 as by means of the springs 17 located within the sockets 18 and forcing the lugs 19 downwards. These lugs bear directly against the top of the corresponding cross block 16, as clearly shown in Fig. 4. Each cross block 16 carries a pair of rollers 20 and 21, respectively, mounted on shafts 24, which rollers are placed directly above the positions of the conveyor chains 9 and 10, respectively. Consequently, the veneer strips are firmly held against the respective conveyor chains. The two veneer strips 22 and 23 are illustrated in place on the table in Fig. 4. Their adjoining ends are in direct contact at a point intermediate between the two conveyors.

The blocks 16 carry the shoes 25 which bear down against a longitudinally extending central plate or bar 25^a which is located directly above the adjoining edge portions 5 of the veneer strips. This plate or block 25^a is preferably heated in any convenient manner, as, for example, by the use of electric resistance wires, 25^b.

Beneath the position of the plate or block 10 25^a there may be located another heating element 26 embedded directly within the table and serving to heat the underside of the veneer joint.

The veneer strips are fed into the machine 15 in a condition of almost complete parallelism, their adjoining edges being simultaneously coated with the proper adhesive. Owing to the converging positions of the two conveyors 9 and 10, the conveyor strips are 20 worked into firm solid edge engagement and are directly edge united by the adhesive on their edges.

The adhesive is conveniently placed upon the edges of the strips by the use of a small 25 thin disk 27 of tapering thickness, as shown particularly in Figs. 3 and 5. This disk is journaled in a pair of blocks 28 and 29 which are countersunk into the top face of the table, the edge portion of the disk projecting 30 slightly above the surface of the table.

Beneath the table is a glue pot 30 into which the lower portion of the disk projects and from which a continuous supply of adhesive 35 is available. As the veneer strips are worked into the machine, their edges come against the sides of the wheel or roller 27 and are preferably treated with adhesive, the wheel also serving to hold the strips in 40 spaced relation at this point, and preventing a tendency for the edges to overlap one another. They then travel underneath the shoe 25^a and are simultaneously carried into firm edge engagement. As they travel beneath 45 the shoe they are heated to the proper point to insure the chemical reaction which results in "setting" the adhesive.

If desired, the roller 27 may be driven positively from the same power supply as 50 is used for operating the conveyors. For this purpose, I have illustrated the driving connections in Fig. 1, which include a small shaft 31 driven by a worm gear drive 32 from the shaft 33 on which the pulley 15 is 55 mounted.

While I have herein shown and described only certain embodiments of the features of my present invention, still I do not intend to limit myself to the same, except as I may 60 do so in the claims.

I claim:

1. In a machine of the class described, the combination of a work table, a pair of horizontally traveling conveyors located close to each other in the top surface of the same,

and mounted for travel in directions converging slightly towards each other and adapted to carry the adjacent portions of a pair of veneer strips into direct edge contact with each other, spring pressed rollers above the 70 positions of said conveyors for firmly clamping the veneer strips thereagainst, a wheel mounted for rotation about a horizontal transverse axis at a position between the more separated ends of the conveyors, said 75 disk tapering in thickness, a glue pot beneath the disk and serving to deliver glue onto the faces thereof, a presser foot above the table at a position intermediate between the conveyors and adapted to firmly contact 80 the top surfaces of the veneer strips undergoing treatment, and means for heating said presser foot for the purpose specified, substantially as described.

2. In a machine of the class described, the 85 combination of a work table, a pair of horizontally traveling conveyors located close to each other in the top surface of the same and mounted for travel in directions converging slightly towards each other and adapted to 90 carry the adjacent portions of a pair of veneer strips into direct edge contact with each other, presser means above the positions of said conveyors for firmly clamping the veneer strips thereagainst, glue carrying 95 means located between the more separated ends of the conveyors and adapted to hold the strips in separated relation at that point and to deliver glue onto the edges of the veneer strips, a presser foot above the table 100 at a position intermediate between the conveyors and adapted to firmly contact the top surfaces of the veneer strips undergoing treatment, and means for heating the presser foot for the purpose specified, substantially 105 as described.

3. In a machine of the class described, the combination of a work table, means for feeding two veneer strips forwardly and in converging relation to one another, and a gluing 110 device extending above the surface of said table between said feeding means and in position to apply glue to the edges of the veneer strips and to hold said edges in separated relation at said point and to permit said edges to come into butt contact with one another in advance of said point, substantially 115 as described.

4. In a machine of the class described, the combination of a table, companion feeding 120 devices on opposite sides of the feeding line along said table, said feeding devices acting in opposition to one another to feed two veneer strips forwardly and in converging relation to one another, and a gluing device extending above the surface of said table between said feeding means and in position to apply glue to the edges of the veneer strips and to hold said edges in separated relation 125 at said point and to permit said edges to 130

come into butt contact with one another in advance of said point, substantially as described.

5. In a machine of the class described, the combination of a table, companion feeding devices on opposite sides of the feeding line along said table, said feeding devices acting in opposition to one another to feed two veneer strips forwardly and in converging relation to one another, a gluing wheel having its upper portion protruding above the surface of said table, and a glue receptacle below the surface of said table into which said wheel extends, the wheel being located in the feeding line at a point to the rear of the intended point of contact for the edges of the veneer strips and serving to apply glue to said edges, and serving to hold said edges in separated relation behind the intended point of contact with one another, substantially as described.
- 10
- 15
- 20

6. In a machine of the class described, the combination of a table, companion feeding devices on opposite sides of the feeding line along said table, said feeding devices acting in opposition to one another to feed two veneer strips forwardly and in converging relation to one another, a gluing wheel having its upper portion protruding above the surface of said table, a glue receptacle below the surface of said table into which said wheel extends, the wheel being located in the feeding line at a point to the rear of the intended point of contact for the edges of the veneer strips and serving to apply glue to said edges, and serving to hold said edges in separated relation behind the intended point of contact with one another, and presser means above the line of edge contact of the veneer strips and serving to impart pressure thereto, substantially as described.

JOHN E. BLACK.
